UNITED STATES PATENT OFFICE.

HERBERT L. LYLE, OF BROOKVILLE, PENNSYLVANIA.

RAIL JOINT.

Application filed November 17, 1921. Serial No. 515,828.

To all whom it may concern:

Be it known that I, HERBERT L. LYLE, a citizen of the United States, residing at Brookville, in the county of Jefferson and 5 State of Pennsylvania, have invented certain new and useful Improvements in Rail Joints, of which the following is a specification.

My invention relates to rail joints adapted to take care of expansion caused by changes 10 in temperature, as well as of contraction of the rails, after they have been laid.

One object of the invention is now to furnish fish plates integral with the rail ends instead of detachable therefrom. As these 15 solid fish plates extend all the way from the foot up to the head of the rail, the head is well supported and no sagging of the abutting rail ends will occur, when a train is passing along the track, so that all hammering 20 or clicking against the wheels at the joints, will be obviated. On this account, there will be no undue wear at these places, nor will the corners of the rails break off.

Another advantage is to be found in the 25 fact that the extending fish plates on one rail embrace and tightly grip the web of the adjoining rail, so that no side movement between them is possible.

Still another advantage is gained by this 30 construction, namely that the joint, which generally is the weakest part of the track and for that reason experiences the greatest amount of wear, is here the strongest part of the track.

In the accompanying drawing one embodiment 35 of the invention is illustrated.

Figure 1 shows a side elevation of the joint assembled;

Figure 2 is a similar view, partly in section;

Figure 3 is also a side elevation with the rail ends separated, and partly in section, and

Figure 4 is a transverse section along the 45 line 4—4 of Figure 2.

In the drawing, the most common rail section has been illustrated, that is, a T-section consisting of the head 10, web 11 and flange or foot 12. The left rail end, as seen 50 in Figures 1, 2 and 3, has the head 10 and part of the web 11 cut away, as best seen

in Figure 3, but the lower half of the web from a medial line 13 down to and including the foot projects a considerable distance to the right, as seen in the drawing, from the 55 perpendicular surface 14 where the head and part of the web have been cut away. In this manner, a lower extension 15 is formed which, to about midway of its length, is provided with a recess 16.

A pair of reinforcing wings 17 having approximately the shape of ordinary fish plates, are welded to the rail end and extend in a perpendicular direction the full distance between the head 10 and the foot 12. 60 In this manner, the reinforcing plates are able to give a firm support to the head of the rail end. Lengthways the reinforcing plates 17 extend with half the length to the left of the abutment surface 14 and with the 65 other half to the right of said surface. In this manner, a solid body is formed to the left of the surface 14 and a channel 19 is formed between the free ends of the right hand ends by these reinforcing plates. This 70 channel 19 is of the same width as the web 11.

The right hand end of the rail joint, as seen in the drawing, is shaped in the opposite way to the left rail end, that is to say, the head portion 10 in this case extends beyond 75 the foot portion 12 a corresponding amount to the cut-away portions in the left rail end. The web is, therefore, cut along the longitudinal medial line 20 and formed with a lug 21, which is slightly shorter in 80 length than the corresponding recess 16 in the left hand rail end, but the overhanging portion of the right hand rail end up to the abutment surface 22 is of the same length as the extending portion 15 of the left rail 85 end.

The right hand rail end is also provided with a pair of reinforcing plates 23 constructed in the same manner as the reinforcing plates 17 and these plates 23 are welded 90 to the right hand rail end, so that about half of the length of the plates form a solid body with the head, web and foot of the right rail end, while the left ends of the plates form an inverted channel between 95 them adapted to engage the web of the left rail end when the parts are assembled.

As best seen in Figure 2, the rail ends are assembled, so that the webs of the two extending ends engage along the medial lines 13 and 20 and the projection 21 engages in the recess 16, so that the perpendicular surfaces 14 and 25 abut against each other leaving a small play to the rear, as at 26, in the longitudinal direction in order to permit contraction of the rails when in position. As best seen in Figure 4, the web 11 then fits tightly in the channel 19 formed between the reinforcing plates 17 and similarly the web on the lower extension fits tightly between the walls of the inverted channel formed by the reinforcing plates 23. This causes a firm support in lateral direction of the rail, so that no slipping at the joint is possible in that direction. As the top faces 27 of the reinforcing plates 17 engage snugly under the head 10, on the one hand, and the bottom faces 28 of the reinforcing plates 23 also fit tightly over the foot 12 on the other hand, a firm support is provided between the head and foot of the rails at the joint. It will, therefore, be seen that no displacement in perpendicular direction of the top surfaces of the rail ends is likely to occur and that, consequently, all hammering at the joint in this manner has been obviated.

Should the rails expand during hot weather, so that they would bulge, the length of the rails can easily be adjusted by cutting off the end of the right hand rail sufficiently, as indicated by line 29. A similar shortening of the left hand rail end is indicated in Figure 3, where the extending part of the rail end should be cut along line 31 and the same length added in the recess 16, as indicated at 32. When this operation has been performed, the joint is again assembled, and the parts will fit together as before, permitting the same amount of play 26 as before in the longitudinal direction in case of subsequent contraction of the rails.

It will be evident, that the invention is equally applicable to different sections of rails and that the claims are intended to cover modifications necessary in that respect.

Having thus described the invention, what is claimed as new is:

1. In a rail joint, a rail end having an overlapping top portion and another rail end having a corresponding overlapping bottom portion, a pair of fish plates integral with each of said rail ends and extending part way along said overlapping portions and adapted to embrace the corresponding web of the opposing overlapping portion.
2. In a rail joint, a rail end having an overlapping top portion and another rail end having a corresponding overlapping bottom portion, said overlapping portions meeting along a medial longitudinal plane of the rail webs, and a pair of fish plates integral with each of said rail ends and extending

part way along said overlapping portions and adapted to embrace the corresponding web of the opposing overlapping portion.

3. In a rail joint, a rail end having an overlapping top portion and another rail end having a corresponding overlapping bottom portion, said overlapping portions meeting along a medial longitudinal plane of the rail webs, one of said portions having a recess and the other portion a corresponding projection, and a pair of fish plates integral with each of said rail ends and extending part way along said overlapping portions and adapted to embrace the corresponding web of the opposing overlapping portion.

4. In a rail joint, a rail end having an overlapping top portion and another rail end having a corresponding overlapping bottom portion, said overlapping portions meeting along a medial longitudinal plane of the rail webs, one of said portions having a recess and the other portion a corresponding projection permitting a slight longitudinal play, and a pair of fish plates integral with each of said rail ends and extending part way along said overlapping portions and adapted to embrace the corresponding web of the opposing overlapping portion.

5. In a rail joint, a rail end having an overlapping top portion and another rail end having a corresponding overlapping bottom portion, said overlapping portions meeting along a medial longitudinal plane of the rail webs, and a pair of fish plates integral with each of said rail ends and extending part way along said overlapping portions and adapted to embrace the corresponding web of the opposing overlapping portion, said fish plates filling the space between the foot and the head of the rail, thereby providing a firm support for the head and preventing sagging at the joint.

6. In a rail joint, a rail end having an overlapping top portion and another rail end having a corresponding overlapping bottom portion, said overlapping portions meeting along a medial longitudinal plane of the rail webs, one of said portions having a recess and the other portion a corresponding projection, and a pair of fish plates integral with each of said rail ends and extending part way along said overlapping portions and adapted to embrace the corresponding web of the opposing overlapping portion, said fish plates filling the space between the foot and the head of the rail, thereby providing a firm support for the head and preventing sagging at the joint.

7. In a rail joint, a rail end having an overlapping top portion and another rail end having a corresponding overlapping bottom portion, said overlapping portions meeting along a medial longitudinal plane of the rail webs, one of said portions having

a recess and the other portion a corresponding projection permitting a slight longitudinal play, and a pair of fish plates integral with each of said rail ends and extending 5 part way along said overlapping portions and adapted to embrace the corresponding web of the opposing overlapping portion,

said fish plates filling the space between the foot and the head of the rail, thereby providing a firm support for the head and preventing sagging at the joint. 10

In testimony whereof I affix my signature.
